FLUSH VALVE

William E. Sloan, River Forest, and Irving H. Russell, Oak Park, Ill., assignors to Sloan Valve Company, Chicago, Ill., a corporation of Illinois

Application February 28, 1938, Serial No. 192,944

1 Claim. (Cl. 137—111)

Our invention relates to flush valves, and has as its general object the provision of a flush valve which may be readily adapted to be installed in a number of positions and which is relatively silent in operation.

One specific object of the invention is the production of a flush valve having a water inlet in one side of the casing and having a handle which may be mounted in the side of the casing in a plurality of positions with respect to the position of the inlet opening, whereby the handle may be located at the side of the flush valve with the water inlet positioned either to the right, to the left, or to the rear of the flush valve. In carrying out this object, one handle opening is provided on the side opposite the inlet opening, and a second handle opening is provided displaced a quarter of a turn from the first. In this way, when the flush valve is installed with the inlet located in any one of the three customary positions above enumerated, one or the other of the two handle openings comes in such a position that the handle can be placed therein and extend along parallel to the wall through which the supply pipe is brought.

A further specific object of our invention is the production of a new and improved air-inlet device or vacuum breaker which is fitted into whichever handle opening is not used by the flush valve handle to serve the dual purpose of admitting air readily to the flush valve interior under conditions tending to cause back-siphonage, as well as to admit air to the interior of the flush valve below the seat thereof near the end of the flushing operation, so as to largely eliminate what are commonly referred to as the approach and refill noises.

It is a further specific object of our invention to provide the air-intake device with a suitable muffler which effectively silences the sound which is otherwise created by virtue of the air being drawn into the flush valve interior through the air-inlet device near the end of the operation of the flush valve. This air-noise muffler conveniently takes the form of a renewable cartridge of relatively loose filler material having a relatively large surface exposed through which the air may flow in quite readily, but which has a deadening effect upon sound tending to reach the outside of the flush valve.

Other objects and features of our invention, more or less incidental to those above set forth, will appear upon a further perusal of the specification. The accompanying drawings, comprising Figures 1 to 11, show sufficient details of ap-

paratus constructed in accordance with the invention to enable the invention to be understood.

Figures 1 and 2 show a side view (partly in section) and a bottom view (partly in section) of one form of the improved flush valve;

Figures 3 and 4 show corresponding views of the casing of the flush valve with a modified construction of the barrel or cylinder which confines the guide wings of the flush valve;

Figures 5 and 6 show a top view and a front view, respectively, of an installation in which the improved flush valve is used with the supply coming to the flush valve from the right, the operating handle being located on the left;

Figure 7 shows a top view of the improved flush valve as it appears when the supply line reaches the inlet opening from the left, the operating handle extending to the right;

Figure 8 shows an installation in which the supply line reaches the improved flush valve from the rear, the operating handle extending to the right;

Figure 9 is a double-scale sectional view of the vacuum breaker or inlet valve mechanism 16 of Fig. 1;

Figure 10 is a sectional view taken along the line 10—10 of Fig. 9 in the direction indicated by the arrowheads; and

Figure 11 is a double-scale front view of the muffler or filter element 18.

Referring now particularly to Figs. 1 and 2, the flush valve shown therein has a body or casing indicated generally by the reference numeral

35 1, and a threaded inlet opening 2, and a slip joint outlet 3. The valve is provided with a finishing cap 4, held in place by the cap nut 5. The water discharged through the flush valve passes through

40 the discharge tube 6, held in place by the coupling nut 7 which compresses the illustrated sealing gasket to seal the flush pipe and retain it in place in the customary manner.

The main valve 8 is normally in engagement with the main seat 9, with the refill head 10 extending within the opening through the main seat and through the associated guide barrel 12, the lower end of the main-valve assembly being guided in the guide barrel 12 by the guide wings 11.

50 The stem 13 of the usual relief valve (not shown) is actuated by the horizontally extending plunger 15 of the handle assembly 14, when the handle is operated. The operation of this stem by the handle causes the main valve 8 to rise in the well-known manner responsive to line pres-

sure until the refill head 10 is brought out of the main seat 9 the desired distance so as to provide a sufficient opening for the flow of water to the fixture to be flushed. Upon the release of the handle, and the consequent restoration of handle plunger 15 and relief-valve stem 13, the main valve 8 makes its usual and well-known slow descent until it comes to rest again upon the main seat 9.

In the usual installation, the rate of flow through the flush valve in its full open position is throttled more or less according to the line pressure by the associated individual throttle valve or stop valve, such as 28 in Figs. 5 and 6, the rate of flow being adjusted according to the requirements of the closet bowl or other receptacle being flushed.

It is well understood that sufficient water must be left in the bowl when flushing action is completed to provide the required seal against the escape of sewer gas, the water required for this purpose being known as refill water. The water for refilling the bowl flows after the refill head 10 has entered the opening in the main seat 9 during the time required for the main valve 8 to travel the remaining distance to its seat. Because of the relatively small clearance between the refill head and the main seat 9, the rate of flow during the refilling operation is very much less than the rate of flow during the flushing operation, whereby the receptacle being flushed does not siphon again and carry out the refill water. When the refill head is approaching the main seat, the relatively low back pressure offered by the flush valve during the main flushing operation is increased until it becomes a large fraction of the line pressure by the time the refill head 10 has entered the opening through the main seat and through the guide barrel. As the pressure builds up, the velocity of the water passing through the flush valve is greatly increased, and this high velocity of the water passing through the restricted opening ordinarily gives rise to pronounced and objectionable noises which are emitted not only in the room where the flush valve is installed, but travel along the piping system to cause more or less annoyance to other occupants of the building. The characteristic sound produced as the refill head is approaching the main seat is commonly referred to as the "approach" noise, while the characteristic sound produced after the refill head has entered and before the valve is fully seated is commonly referred to as the "refill" noise.

During tests made with a view of discovering how to minimize the approach and refill noises, it was discovered that these noises are largely eliminated when an opening is made through the casing below the main seat to admit air to the interior of the casing. It was found that the movement of the water at the relatively high velocities which occur during the approach and refilling operations, aided by the weight of the water falling through the discharge tube, creates a sub-atmospheric condition in the portion of the casing below the main seat, resulting in the drawing in of air during the approach and refilling operations. The air thus automatically drawn in at a time when the noise would otherwise be generated serves to inhibit the generation of noise at this time. It may be noted that the velocity of the water during the main flushing operation is sufficiently low that the sub-atmospheric condition is not noticeably brought about and that the sub-atmospheric condition seems to appear at

about the same point at which the velocity reaches the noise-making value.

It was soon found that a simple hole in the side of the casing between the outlet and main seat 9, although it sufficed to effectively silence the approach and refill operations, could not be tolerated because of the leakage out through this hole during the main flushing operation when the rate of flow is such that more or less back pressure is offered by the fixture being flushed. For this purpose, the vacuum breaker device 16 was developed to be placed in one of the two handle openings previously discussed. As will be pointed out more fully hereinafter, the vacuum-breaking device 16 has an air-intake passage leading from the outside into the interior of the discharge chamber and is provided with a normally closed check-valve 37, which prevents the flow of water out through the air-intake opening during the main flushing operation, while being lifted readily by the outside air pressure when the sub-atmospheric condition is brought about in the discharge chamber of the flush valve at the beginning of the approach to the refill position. At this time, air is drawn in through the inlet hole 29 in the retainer cap 17, through the muffler or filter 18, up through the check-valve 37, raising the check-valve off its seat, and thence into the discharge chamber of the flush valve by way of the exit hole 19 of the vacuum-breaking device.

In order that the admitted air have the fullest opportunity to circulate in the swirling water in the discharge chamber and rise to a point close to the main seat, the bottom portion of the barrel 12 is cut away around nearly half the circumference, as may be seen upon reference to Fig. 2 and upon noting the dotted line behind the refill head 10 in Fig. 1. This cutaway portion of the barrel 12 is so located as to face both the handle openings A and B in the casing, so that the indrawn air will be free to rise to its fullest extent in whichever position the vacuum-breaking device 16 may be installed, the handle, of course, occupying the other position. The portion of the barrel which is left of full vertical extent is sufficient to support at least two of the guide wings 11, as may be seen in Fig. 2. There is, of course, some side thrust upon the main valve and the guide wings 11 when the handle plunger 15 engages the stem 13 of the relief valve upon an operation of the handle, but it is to be noted that the barrel is of full height opposite the handle to receive this thrust of the guide wings, no matter in which of the two openings the handle may be installed.

Referring now particularly to Figs. 3 and 4, these drawings show a casing for a flush valve, as in Figs. 1 and 2, in which the reduction in the height of the barrel 12 opposite the handle and refill openings (indicated in Fig. 3 as 12') is only slight, whereby all four of the guide wings 11 are confined within the barrel; thus the usual full guiding is not interfered with. Tests have indicated that the barrel arrangement of Figs. 3 and 4, with its superior guiding, is about as satisfactory from the silencing standpoint as the barrel arrangement of Figs. 1 and 2, provided the air-intake passage is sufficiently large to admit the somewhat increased amount of air required with the modified barrel arrangement.

Referring now particularly to Figs. 5 and 6, it will be noted that the supply pipe 26 extends out of the wall sufficiently to engage the inlet of the throttle or stop valve 28, the exit from

the wall being covered by the usual wall-flange 21. The outlet of the stop valve 28 extends horizontally along the wall and is connected with the inlet 2 of the flush valve by means of the usual tail piece and ground-joint union. The supply connection thus reaches the flush valve in this installation from the right. Since it is desired to have the handle extend along the wall and not protrude out into the room, the handle assembly 14 in Figs. 5 and 6 is placed in opening A, while the vacuum breaker or air-inlet assembly, whose retainer cap 17 is shown in Figs. 5 and 6, is placed in opening B.

In Fig. 7, the supply pipe and stop 28 are located to the left of the flush valve, necessitating that the flush valve be turned around as illustrated. In this case also, the handle assembly 14 is located in opening A, while the vacuum breaker is placed in opening B.

It sometimes happens that the supply pipe is brought out of the wall directly behind the flush valve, as is indicated in Fig. 8, a so-called straight stop 28' being inserted between the supply pipe and the flush valve. In this installation, the handle assembly 14 is moved around from opening A to opening B, while the vacuum-breaker assembly, indicated by the retainer cap 17, is placed in opening A.

It will thus be seen that the improved flush valve, with alternative openings for the handle, enables a single style of flush valve casing or body to meet the three common conditions of installation illustrated in Figs. 6 to 8, in that the vacuum-breaker assembly and the handle assembly may be interchangeably mounted in the two openings provided for this purpose; the preferred position of the handle, extending along parallel to the wall, being retained in each of the three common types of flush-valve installation.

Referring now particularly to Figs. 9 to 11, the air-inlet or vacuum-breaking device will be described more in detail. This device is illustrated as installed in the position shown in Figs. 1 and 2, but is shown double-scale in Figs. 9 to 11 for clarity. The body 16 of the vacuum-breaker assembly is preferably molded of a substance having molding characteristics such as those of the material known commercially as "Bakelite." The body 16 has the general form of a washer or disc of a diameter only slightly less than the diameter of the face of the opening A in the casing 1. The body is held in place by the retainer cap 17, while the gasket 43 acts as a seal between the body 16 and the face of the opening in which it is held.

In order to maintain the vacuum-breaker assembly 16 in its required upright position, the bottom of the opening A (and the same is true for the bottom of the opening B) has a keyway 47 therein which receives a corresponding key 46 formed in the shell-like cover 21. A key-rib 45 is formed on the bottom of the body 16 to extend into the depressed keyway produced inside the shell 21 upon the formation of the said key 46.

The main body portion 16 has the connected ribs 41 and 42 formed thereon to inclose the vertical air passage 36, and to provide the raised seat 39 for the air valve 37, as well as to act as a baffle to prevent any possible splashing of water onto the valve seat.

The rivet 40 is cast into the rib 42. This rivet has a hollow outer end which is turned over as illustrated to retain the shell 21 in position.

The air valve 37 is provided with a seating portion 38 which is preferably of live soft rubber. 75

The upper end 44 of the square-shaped guide stem for the air valve provides a stop against the shell 21 to prevent the air valve from being drawn out of the passage 36 when there is a large inrush of air.

The muffler or filter 18, illustrated best in Figs. 9 and 11, is preferably of loosely felted filler material 32, contained within the ringlike container 33, and held in place by the discs 30 and 31 of coarse, open-mesh, wire cloth.

Air entering through hole 29 in the retaining cap 17 may pass freely to any part of the outside surface of the muffler and thence pass through the deadening filler material 32 to the inside of the muffler 18. From this point, the air may pass freely to the horizontal passage 35, and thence to the vertical passage 36. When the pressure within the outlet chamber of the flush valve is more or less below atmospheric pressure, this reduced pressure is transmitted through the exit hole 19 of the vacuum-breaking device to the interior of the shell 21. Under this condition, the normal atmospheric pressure, operating on the bottom of the valve, raises the valve 37 easily from its seat and thus permits air to flow freely to the interior. At all other times, the valve 37 is reliably seated, with the soft seating part 38 on the sharp raised seat 39.

It is to be noted that the open end of the cover 21 is outwardly flanged, and that it lies in a recess which brings its face in line with the sealing face of the body 16. By this arrangement, the gasket 43 also seals between the body 16 and the cover 21. The cover 21 thus defines an air chamber which prevents water from reaching and damaging the air-valve seat. The exit from the interior of the vacuum-breaker structure to the interior of the flush valve casing is at the bottom of cover 21, through the exit hole 19. The danger of water splashing into the shell 21 and reaching the air valve when the air valve is seated is thus minimized. This possibility is rendered still more remote by the baffle-like construction of the ledge or rib 41 which extends on both sides of the seat 39 and thus nearly fills the interior of the shell 21 at the height of the seat, but leaving ample clearance for air passage between the shelf 41 and the inside of the shell 21.

By selecting the filler material 32 of the muffler with regard to its looseness, the rate at which air is drawn in is suitably controlled so that no noticeable noise is produced. Being provided with a relatively large surface as compared to the area of the air passage, the muffler 18 is in very little danger of clogging up as a result of particles contained in the indrawn air. The shell or cover 21 assists in deadening splashing sounds tending to reach the outside through the air inlet.

In addition to having a retarding and quieting effect upon the velocity of the air drawn in, the muffler 18 has a deadening effect upon sounds tending to penetrate to the outside of the flush valve casing, occasioned by the splashing of water therein, which sounds might be otherwise somewhat noticeable in the event of a direct unmuffled opening through the casing wall.

What we claim is:

In a valve structure for controlling the discharge of liquids from a source under pressure including a casing having a valve seat therein and a valve movable toward and away from said seat, there being a guide barrel positioned around the valve seat in the casing and downstream of the seat, a guiding part fixed to the valve and ex-

tending within the guide barrel to guide the valve in its movement toward and away from the valve seat, the guide barrel opening into a discharge chamber having an outlet remote from the valve seat, there being an air opening into the side of the discharge chamber to admit air into the discharge chamber when the velocity of the water passing between the valve and its seat is great enough to cause a reduced pressure within the discharge chamber and the consequent danger 10

of a noisy flow in the said discharge chamber, there being an opening through the side of said barrel from the discharge chamber to allow the admitted air to pass along the side of the discharge chamber in a convection current up to the vicinity of the valve seat, whereby the generation of noise due to the high velocity flow is substantially prevented.
